PNEUMATIC CLEANER

Joseph A. Dietenberger, Cleveland, Ohio, assignor,
by mesne assignments, to Electrolux Corporation, Dover, Del., a corporation of Delaware

Application November 29, 1929, Serial No. 410,404

9 Claims. (Cl. 15—14)

This invention relates to electric vacuum cleaners and has for its objects: the provision of an inexpensive compact and simple device of this nature which shall be capable of easy manufacture and made and assembled cheaply, with a minimum of expensive parts, which shall afford a high suction, and be readily emptied and cleaned; the provision of a cleaner which will either blow or suck through the nozzle opening thus enabling lint and dust to be removed from cracks and crevices from which suction alone is unable to dislodge it; the provision of simple and self-contained arrangements whereby the device can be changed from suction to blowing and vice versa instantaneously; the provision of a tank or can type of cleaner having the hose as well as all other working parts carried by the cover to facilitate manufacture and manipulation; the provision of a new and improved construction and arrangement of parts; while further objects and advantages of the invention will become apparent as the description proceeds.

In the drawings accompanying and forming a part of this application I have shown certain simple and practical forms in which my inventive idea can be embodied, although it will be understood that my inventive idea could be utilized in many other forms and that these drawings are intended to be merely illustrative and not limiting upon me. Fig. 1 is a vertical sectional view through one embodiment of my invention corresponding to the line 1—1 of Figs. 3 and 4; Fig. 2 is a detail sectional view corresponding to the curved line 2—2 of Fig. 4; Fig. 3 is a top plan view of the cleaner shown at Fig. 1 drawn to smaller scale and omitting a part of the hose; Figs. 4 and 5 are horizontal sectional views corresponding to the lines 4—4 and 5—5 respectively of Fig. 1 but drawn to smaller scale; Figs. 6 and 7 are horizontal sectional views through the valve illustrated in Fig. 2, showing the same in suction and blowing positions, respectively; Fig. 8 is a detail sectional view corresponding to the line 8—8 of Fig. 3; Fig. 9 is a sectional view similar to Fig. 2 but showing a modified form of casing-top and hose-connection; Fig. 10 is a perspective view of the modified form of cleaner shown in Fig. 9, illustrating the same in use. Fig. 11 is a top plan view of the reversing valve used with this modification; Fig. 12 is a vertical section corresponding to the line 12—12 of Fig. 11; and Figs. 13 and 14 are sectional views corresponding to the lines 13—13 of Fig. 12 but showing the reverse valve in different positions.

The casing of my improved cleaner consists of an open-topped, sheet-metal receptacle 1, terminating at its upper edge in a wire rim 2 and having suitable floor-supports 3—3, such as rubber-balls set in embossed recesses 4—4 and held in place by metal rings 5. Tightly secured to the top of this receptacle is a cover which carries all the mechanism. In its present form this cover comprises a flat plate 5 of any suitable material (metal, presswood, bakelite, etc.), having at its outer edge a downwardly facing groove 6 receiving the rim 2 and also suitable packing 7. Depending from the bottom face of the plate 5 is a wall 8 defining a fan-chamber 9. This wall is preferably not circular but shaped somewhat like a spiral as shown in Fig. 4, its portion 10 of greatest radius defining the outer wall of a peripheral outlet-neck 11. Formed adjacent to the fan-chamber 9 is a valve-chamber 12 as shown in Figs. 2, 4, 6, and 7. This chamber defines a surface of revolution perpendicular to the plane of the plate 5. The outlet-passage 11 opens into one side of this valve-chamber by way of the port 13. Between this port and the wall 8 of the fan-chamber is a second port 14 which opens into the angular space 15 defined between the wall 8 and the adjacent wall of the outlet neck. On the opposite side of the valve-chamber from the port 13 is the port 16 from which leads the passageway 17 slanting upwardly through the cover 5 and terminating in a nipple 18 to which is attached the suction hose 19. This nipple is preferably caused to project parallel with the top of the plate 5 and tangentially to its edge to facilitate the coiling of the hose on the cover-top when not in use; and the better to dispose of this hose the cover is provided with a plurality of pivoted clips 20 arranged at suitable distances about the same and adapted when erected to form posts to hold this hose in place, or upon the removal of the hose to be folded downwardly out of the way as shown in dotted lines in Fig. 8. The cover is secured to the receptacle by any suitable clips or fasteners 29 and is itself provided with a handle 49, accessible as well with as without the presence of the hose, whereby the cleaner can be carried about.

In the present embodiment the bottom face of the fan-chamber is formed with a circular opening 21 of sufficient size to enable the insertion of 50 the fan (see Figs. 1 and 4) which is closed by a metal plate 22 formed at its center with an aperture 23 forming an inlet for the fan-chamber, and provided at its outer edge with a circular end- 55 less rim 24 for a purpose to be described hereafter.

Secured to the face of the plate 22 opposite the wall 8 is a metal casing 25 constituting another fan-chamber 26 concentric with the fan-chamber 9 and having a flat bottom face 27 formed with 5 a central inlet opening 28.

Secured to and depending from the plate 27 is 10 a spider 30 to which is secured the electric-motor indicated generally at 31; and carried by the opposite or lower end of said motor is a spider 32 terminating in a circular ring 33 of substantially equal diameter to the rim 24, and extending near to but out of contact with the bottom of the casing 1. The ring 33 constitutes a support and spreader for the dust-filter 35, which consists of 15 a bag of cloth, paper, or similar pervious material, having at its upper edge a hem 36 in which is received a coil-spring 37, rubber-band, or other constricting device which holds the open end of the bag tightly on the rim 24.

20 The motor-shaft 38 passes freely through the openings 28 and 23 and is provided inside each of the fan-chambers with a suitable fan of centrifugal type, preferably comprising a plurality of radial blades 39 carried by a flat circular disk 40 fastened to the motor-shaft, and having secured to their opposite edges a centrally apertured plate 41. This makes what is known as a "shrouded fan" and if the apertures 23 and 28 are surrounded by annular flanges 42 and 43, respectively, projecting into the apertures of the plates 41, 41, the fans are rendered very efficient. Besides, the two-stage arrangement produces a very powerful action capable of working through a long hose.

25 Formed in the top-plate 5 is an opening 44 communicating with the space 15. The bottom end of the valve-chamber 12 is closed by a flat wall 45 which is formed with an aperture 46 in line with the ports 13 and 16 and adjacent to the port 16; 30 also with an aperture 47 located inwardly of the aperture 46. Aperture 46 opens into the annular space outside of the filter-screen (see Fig. 5) and communicates with an elbow 48 which serves to direct the entering air currents in a horizontal 35 tangential direction. The aperture 47 opens inside the filter-screen as shown in Fig. 5.

30 Located in the valve-chamber 12 is a rotatable valve comprising a flat circular plate 50 fitting in the bottom of the chamber, a vertical diametral partition 51 traversing the chamber, and a circular top 52 overlying the chamber and provided with a handle 53 whereby the valve may be turned. Preferably the top 52 is formed at each side of this handle with an aperture 54 closed by 35 a transparent plate 55 to constitute an inspection-window, whereby the passage of the dust is rendered visible. In addition the plate 50 is formed at one point with an aperture 56 adapted, when, the partition 51 stands cross-wise of the outlet neck, as illustrated in Figs. 2, 3, and 6, to register with the opening 46. With the parts in this position, air can enter by way of the hose 19, passage 17, port 16, apertures 56 and 46 and nipple 48 into the annular space surrounding the filter 45 35. The air passing through this filter, after traversing the fans in series, escapes by the passage-way 11, ports 13 and 14, and aperture 44 in the top plate. This top plate is provided with suitable indicia as indicated at 57 in Fig. 3 to establish the positions of the valve. If the user desires to cause the air to issue from the hose in the form of a blast, the valve is merely turned at right angles as shown in Fig. 7 to locate the partition 51 parallel to the neck 11 and to cause the aperture 56 to register with the aperture 47, whereupon

the air issuing from the outlet 11 passes directly to the conduit 17, while the air necessary to the supply of the fans enters by way of aperture 44, port 14, and aperture 47 into the interior of the filter-cell which is free from dust so that a clean 5 blast is always obtained.

In Figs. 9 to 14 inclusive I have shown a different arrangement whereby the construction of the casing is simplified and the reversing-valve carried directly by the cleaning-tool. In this form 10 of the invention the top 52 of the casing is provided with two hose-nipples, one 18* communicating as before with the outlet-neck 11* of the pump by way of an inclined passage 17*. The other nipple 60 communicates with the elbow 48 15 which, as before, opens into the dust-chamber. These two nipples are located preferably closely adjacent to and parallel with each other and from them lead two flexible hoses 19* and 61. When these nipples are located one above the other and 20 tangent to the rim of the cover it facilitates coiling them in place when not in use.

The cleaning tool in this embodiment comprises a valve-casing 62, formed as a surface of revolution, having a hollow hand-grip 63 projecting from 25 one side and communicating therewith by way of the port 14*, and a tool connection 64 projecting from the opposite side, also hollow and opening into the valve-casing by way of a port 16*. The bottom of this valve-chamber is closed by a flat 30 wall 45* which is formed with two nipples, 65 and 66, to which are attached the ends of the hose 19* and 61, respectively. These nipples open into the valve-chamber through ports 13* and 46* respectively. 35

Rotatably mounted in the valve-chamber is a valve-member comprising a vertical diametral partition 61* traversing the chamber and a circular top 52* overlying its upper end and knurled or otherwise fashioned to facilitate its rotation by 40 hand. Said top is, as before, formed at each side of the partition with an aperture 54* closed by a transparent plate to constitute an inspection-window. Detachably secured to the connection 64 is the hollow shank 67 of a cleaning tool which 45 may be of any length, size, or character.

In the operation of the device air is constantly blown outwardly through the hose 19* and drawn inwardly through the hose 61. When the valve stands in the position illustrated in Fig. 13 the 50 blast issuing from the port 13* passes through the connection 64 and into the tool, while the suction acting through the port 46* draws air inwardly through the hollow handle 63. When the valve is turned to the position shown in Fig. 14 the suction-port 46* is connected to the tool nipple 64 and the blast-port 13* to the handle 63. Under all conditions the pressure in the litter-chamber and adjacent to the joint between cover and receptacle is sub-atmospheric, so that no tendency 60 exists for any escape of dust even though this joint should not be tight or the fastenings should give way.

I have illustrated different forms of my invention to indicate that my improvements can be 65 embodied in different specific apparatus, and a great many other changes in details, arrangements, and construction can be made without departing from my inventive idea, for which reason I do not limit myself to the constructions herein 70 shown and described excepting as the same are specifically recited in my several claims which I desire may be construed broadly, each independently of limitations contained in other claims. 75

Having thus described my invention what I claim is:

1. In an electric vacuum cleaner, in combination, a receptacle, a cover carried thereby, motor driven suction producing means mounted on said cover, a dust filter carried by said cover inside said receptacle and spaced from the walls thereof, said suction-producing means having its inlet communicating with the interior of said filter and its outlet opening through said cover, said cover also having a suction inlet opening into the space between said filter and the receptacle wall, a hose, and valve means for connecting said hose to either said inlet opening or said outlet opening selectively.

2. A pneumatic cleaner comprising, in combination, a receptacle having a cover, a pumping device and a dust-filter carried by said cover, said pumping device having an inlet and an outlet, and said dust filter communicating with the inlet of said pumping device, a cleaning tool, a flexible hose from said cover to said tool, connections carried by said cover communicating with the outlet of said pumping device and with the space outside said dust-filter, and valve means carried by said cover for establishing communication between said hose and either of said connections selectively.

3. A pneumatic cleaner comprising, in combination, a hollow casing having stiff walls, a filter cell enclosing a part of the space inside said casing, a pump having its inlet communicating with the interior of said filter cell, motor operated means for driving said pump located in said cell, a conduit leading from the pump-outlet, a conduit communicating with the space inside said casing which is outside said filter cell, a cleaning tool, a flexible hose having one end connected to said tool and the other end to said casing, and valve means carried by said casing whereby said hose can be placed in communication with one or the other of said conduits selectively.

4. A pneumatic cleaner comprising, in combination, a hollow casing having stiff walls, a filter cell enclosing a part of the space inside said casing, a pump having its inlet communicating with the interior of said filter cell, motor operated means for driving said pump located in said cell, a conduit leading from the pump-outlet, a conduit communicating with the space inside said casing which is outside said filter cell, a valve casing to

which said conduits are connected, a cleaning tool connected to said valve casing, and a valve member in said casing having ports adapted in one position to connect said tool to one conduit selectively and connect the other conduit to the open air, and in a second position to connect said tool to said other conduit and connect said one conduit to the open air.

5. A pneumatic cleaner comprising, in combination, a hollow casing having stiff walls, a pump carried by one wall and having a circular rim and a supporting bracket, a motor carried by said bracket to one side of said pump and rim, a ring carried by said motor in spaced relation with respect to said rim, and a bag of flexible pervious material surrounding said motor and drawn over said ring and having its mouth constricted around said rim, the space between said bag and the outer wall of said casing constituting a dust chamber.

6. A vacuum cleaner comprising an upright cylindrical dust receptacle having a horizontal, circular cover and a suction hose, a suction pump operatively connected to said hose and receptacle, and a plurality of spaced upright posts carried by said cover adjacent to its margin adapted to have 25 said suction hose coiled inside them.

7. A vacuum cleaner comprising an upright cylindrical dust receptacle having a horizontal, circular cover and a suction hose, a suction pump operatively connected to said hose and receptacle, and a plurality of spaced clips pivoted to said cover at intervals near its margin adapted when raised to constitute posts to retain the hose in place when coiled upon said cover.

8. A vacuum cleaner comprising an upright cylindrical dust receptacle, a suction hose connected to said receptacle adjacent to its periphery and substantially tangent thereto, and a suction pump operatively connected to said hose and receptacle in combination with a series of posts carried by the top of said receptacle adapted to have 40 said hose coiled past the same without unfastening.

9. A vacuum cleaner comprising an upright cylindrical dust receptacle, suction-producing and dust-separating means inside said receptacle, a carrying-handle located at the center of the top of said receptacle, and means for supporting a coil of hose on top of said receptacle surrounding said handle without interfering therewith.

JOSEPH A. DIETENBERGER.
